UNITED STATES PATENT OFFICE.

CHAUNCEY M. CANADA, OF WILLIAMSPORT, PENNSYLVANIA, ASSIGNOR TO UNITED STATES SAND PAPER COMPANY, OF WILLIAMSPORT, PENNSYLVANIA, A CORPORATION OF PENNSYLVANIA.

SANDPAPER HOLDER.

Application filed April 1, 1926. Serial No. 99,153.

For convenience in transporting or shipping and storing sand paper it has been a common practice heretofore to put the same in bales of several reams to the bundle, and 5 recently it has been the practice to put the sand paper in boxes made of pasteboard or cardboard and much trouble and inconvenience has been caused by breakage due to 10 piling the boxes one upon another, for storage or transportation.

Certain objects of my invention are to overcome the objections incident to the use 15 of boxes made of pasteboard or other flexible and breakable material as heretofore for packaging sand paper, and to provide a box of the character referred to which will withstand the pressure of any number of boxes piled one upon another, together with simple and efficient means whereby sand paper 20 may be handled in the original packages conveniently arranged in any desired number and held in separated relation in such manner as to permit easy access to their contents and without danger of crushing or breaking 25 a box by pressure of other boxes thereon due to packing and storing or transporting sand paper in pasteboard boxes piled one upon another in large numbers.

Another object is to provide means whereby 30 the individual boxes may be conveniently handled, whether singly or stacked one upon another, when it is desired to remove a sheet or sheets of sand paper therefrom as needed from time to time, or for the purpose of 35 transporting the boxes from place to place for refilling the same.

The invention will first be hereinafter 40 more particularly described, with reference to the accompanying drawings, which are to be taken as a part of this specification, and then pointed out in the claims at the end of the description.

In said drawings, Fig. 1 is a perspective 45 view of a pasteboard box in course of construction, designed and adapted for use in packaging sand paper for transportation or storage, in accordance with my invention;

Fig. 2 is a detail sectional view taken on the line $x-x$ of Fig. 5;

Fig. 3 is a perspective view of a metallic 50 frame structure designed and adapted to embrace and reinforce a pasteboard box of the character referred to to adapt it to withstand the pressure of a number of boxes piled

thereon, without danger of being crushed or 55 broken;

Fig. 4 is a perspective view of a stack of boxes of the character referred to with reinforcing means thereon; the lowermost box in the stack being partly withdrawn 60 from its reinforcing means and having a hinged end-portion thereof lowered for convenience in removing a sheet or sheets of sand paper therefrom; and

Fig. 5 is a longitudinal vertical sectional 65 view through one of the boxes and its reinforcing means.

Referring to said drawings, in which the same reference letters are used to denote corresponding parts in different views, I have 70 shown in Fig. 1 a piece of pasteboard cut and shaped to form a box having an open top and upturned portions a , a^1 and a^2 , to form the sides and ends, respectively, of the completed box; said end-portions a^2 being 75 turned inwardly and secured together and reinforced by overlapping integral extensions a^3 of the bottom of the box at each end; said extensions being upturned and bent over said end-portion a^2 and then downwardly and having the free end a^4 thereof 80 on the inner side of the box bent substantially at right angles to said downwardly bent portion and secured to the bottom of the box by means of a button-like flap a^5 85 cut out of said bottom and arranged to abut against and overlap said free end-portion a^4 , thus securing the end-portions of the box together. As will be seen the main side 90 portions or sections a of the box are longer than the side portions or sections a^1 , and the upper parts of the latter sections are cut away so that they increase in depth toward the front end-portions a^2 . The bottom of the box is slit or grooved transversely 95 at an intermediate point to form a hinge-like connection so that the front end-portion or extension a^6 thereof may drop down into the position shown in Fig. 4 for removing sand paper therefrom. The box constructed 100 as described is inserted in one end of a container B, also made of pasteboard or the like and having a closed bottom, top, sides and end, but open at one end so that the box with the open top may be inserted therein, and thereupon the assembled parts are inserted within an open frame-work such as 105 shown in Fig. 3 of the drawings, consisting

105

2
 preferably of thin pieces of sheet metal C of angular form in cross-section secured by spot welding or other means, as at c, in the four inner corners of end pieces C¹ of ob-
 5 long rectangular form having horizontal top and bottom portions or bars connected at each end by upright portions c¹, either integral therewith or rigidly secured thereto, as shown, thus forming a crate-like struc-
 10 ture within which the pasteboard box may be inserted to provide a reinforcement therefor while permitting the box to slide back and forth so that it may be readily withdrawn and replaced at will. It will be ob-
 15 served that the end pieces or members C¹ of the crate-like structure are in the form of continuous bands extending around the angle bars or connecting members C at opposite ends thereof and are secured thereto
 20 on the outer sides thereof so that an unobstructed slideway is provided by said connecting members to permit the container B to fit snugly within the crate-like structure and adapt it to be easily inserted at either
 25 end and withdrawn therefrom without coming into contact with the end pieces C¹.

As will be seen, any number of pasteboard boxes of the described construction containing sand paper and reinforced by metallic frame structures of the described form may be piled one upon another, as shown in Fig. 4 of the drawings, without danger of breaking or crushing a box or boxes underneath the pile or stack during transportation or
 30 while in storage for use in removing sheets of sand paper therefrom very much in the same manner that books are removed from an ordinary sectional book-case, by simply partially withdrawing a box from its reinforcing means so that the hinged end portion thereof may drop down into the position shown in Fig. 4 of the drawings for convenience in removing a sheet or sheets of sand paper from the box or re-filling the
 35 same.

For the purpose of withdrawing the pasteboard box having the open top from the container in which it is enclosed, a piece of fabric or other flexible material is glued or
 40 otherwise secured underneath the bottom of the front hinged end-portion of the box to provide a flap or handle D, which may be readily grasped between the thumb and forefinger for pulling the box out of the container.
 45

While I have shown and described as one element of my improved sand paper holder a pasteboard box constructed in a single piece and adapted to serve as the sand paper
 50 holder proper, it will be understood of course that other constructions may be used, as the thing desired is a box similar to the described construction having an open top and a hinged front, and adapted for insertion in an enclosing case or container open at
 55

one end only; the latter being adapted to be inserted in the crate-like reinforcing means having longitudinal and transverse frame members spanning the container along both ends thereof and along its edges on both its upper and its lower sides, so as to prevent the container from being crushed or injured under pressure of superposed boxes in a stack. I also desire it to be understood that the word "pasteboard" as used in the appended claims is intended to include other similar light and flexible material such as cardboard, for example, from which boxes of the character referred to may be easily constructed at very little expense, and which by reason of the character of the material used in their construction require reinforcement to prevent injury thereto when the boxes are piled one upon another with consequent danger of crushing the material of which they are made.

In some cases it may be desirable to use a sand paper holder or box made of pasteboard or other similar flexible and breakable material, without the hinged front end portion, for insertion in a container of the described construction or for insertion in the crate-like reinforcing structure without the container or inner box; my invention in its broader aspects being designed to include such arrangements.

Having thus described my invention, what I claim as new and desire to secure by Letters Patent of the United States is:

1. A reinforced sand paper holder comprising inner and outer boxes made of pasteboard or the like, one slidably inserted within the other; the inner box having an open top and a hinged end-portion adapted to drop down when withdrawn from the outer box; the duplex box being slidably inserted in a crate-like reinforcing structure comprising frame members which extend across and around the ends of the duplex box and other members which extend along the upper and lower longitudinal edges of the duplex box, whereby the assembled boxes are kept intact when piled one upon another while permitting the inner pasteboard box to be partly withdrawn from the outer box for removing sheets of sand paper therefrom or for refilling the same without disturbing the pile; said outer box being adapted to be readily withdrawn from said reinforcing structure together with the inner box and the inner box being adapted to be withdrawn from the outer box without withdrawing the latter from said reinforcing structure.

2. A reinforced sand paper holder comprising inner and outer boxes of shallow form made of pasteboard or other flexible and breakable material, the inner box having an open top and a front hinged end-portion adapted to drop down when partly

withdrawn from the outer box; the latter being open at one end only, and a metallic 5
crate-like reinforcing structure within
which the duplex box is inserted; said structure
having longitudinal and transverse
frame members spanning the outer paste-
board box along its ends and along its edges
on the upper and lower sides thereof, so as
to prevent the pasteboard box from being
crushed or injured under pressure of super-
posed boxes in a stack; said longitudinal
frame members being of angular form and
secured within the four corners of said
transverse frame members; the latter being
in the form of continuous bands extending
around and secured to the outer sides of
said longitudinal members so as to provide
an unobstructed slideway for the insertion
and removal of said holder.

20 3. A reinforced sand paper holder comprising a box of shallow form with open top and hinged front end-portion inserted in a box of similar form open at one end only; said boxes being made of pasteboard or 25 other flexible and breakable material and inserted in a metallic crate-like reinforcing structure having longitudinal and trans-
verse frame members spanning the paste-
board box along both of its ends and along
both of its longitudinal edges on both the
upper and lower sides thereof, so as to prevent
the pasteboard box from being crushed or 30 injured under pressure of superposed
boxes in a stack; said longitudinal frame
members being of angular form and secured
within the four corners of said transverse
frame members; the latter being in the 35 form of continuous bands extending around
and secured to the outer sides of said lon-
gitudinal members so as to provide an un-
obstructed slideway for the insertion and re-
moval of said holder at either end thereof.

40 4. A reinforced sand paper holder comprising two telescopically connected boxes 45 made of pasteboard or the like; the outer box being open at one end only, and the inner box having an open top and a hinged

end-portion adapted to drop down when withdrawn from the outer box, and a reinforcing crate-like structure embracing the 50 duplex box, the latter being slidably inserted in said structure at one end thereof; said crate-like structure consisting of strips of metal which extend transversely across and around the ends of the duplex box, and 55 other strips which extend along the upper and the lower longitudinal edges of said box; said transverse strips being secured to the ends of said longitudinal strips, whereby the assembled boxes are kept intact when 60 piled one upon another in large numbers while permitting the inner box to be partly withdrawn from the outer box for removing sheets of sand paper therefrom or for re-
filling the same without disturbing the pile. 65

5. A reinforced sand paper holder comprising two telescopically connected boxes made of pasteboard or the like; the outer box being open at one end only, and the inner box having an open top and a hinged 70 end-portion adapted to drop down when withdrawn from the outer box, and a reinforcing crate-like structure embracing the duplex box, the latter being slidably inserted in said structure at one end thereof; 75 said crate-like structure consisting of strips of metal which extend transversely across and around the ends of the duplex box, and other strips which extend along the upper and the lower longitudinal edges of said 80 box, said transverse strips being secured to the ends of said longitudinal strips; whereby the assembled boxes are kept intact when piled one upon another in large numbers while permitting the inner box to be partly 85 withdrawn from the outer box for removing sheets of sand paper therefrom or for re-
filling the same without disturbing the pile; said crate-like structure being adapted to permit the duplex box to be inserted there- 90 in at either end thereof.

In testimony whereof I affix my signature.
